COMBINED VEHICLE AIR DEFLECTOR AND SCREEN

Henry Abrams, Minneapolis, Minn.

Application April 23, 1954, Serial No. 30,139

Term of patent 7 years

(Cl. D14—6)

Fig. 1 is a view in front elevation of a combined vehicle air deflector and screen showing my new design;

Fig. 2 is a view in side elevation;

Fig. 3 is a view in rear elevation;

Fig. 4 is a bottom plan; and

Fig. 5 is an enlarged fragmentary section taken substantially on the line 5—5 of Fig. 1.

I claim:

The ornamental design for a combined vehicle air deflector and screen, as shown.
